A. H. Robbins,

Vegetable Cutter.

Patented May 6, 1836.

To the Robbers of Denmark, N. York

Lettered Patent.

The subscriber desires in this letter, patent, and making a part of the same, containing a description in the words of the said subscriber, of Robbers' invention of his improvement in the machine for cutting Potatoes, Turnips, Mangold, swede, Carrot, &c. for cattle and horse feed.

Be it known that I, Abraham Robbers, of Denmark, of the County of Lewis & State of New York, have invented a new and useful machine for cutting Potatoes, Turnips, mangold, swede, &c. for feeding to cattle horses and other domestic animals. The drawing herewith enclosed, is a view in perspective of the model of said machine, on a scale of half an inch to the inch of said model, which is on a scale of three inches to the foot of said machine for use (or nearly).

The principle timber, are four posts, and 3 beam pieces or sides which may be 2 by 3 and a half inches square. The front posts, may be 4 feet 6 inches in length. The rear post 3 feet 6 inches and the beam pieces or sills 2 feet 6 inches in length. In each beam piece between the foot of one post and one rear post leaving a space of $10\frac{1}{2}$ inches between, the end of the beam piece may be extended forward. This post from below the foot of the rear post after the beam piece is cut out a post about 2 inches wide and twenty inches in length, upon the upper side of the post, the opposite end of which is received by the front post, which is very considerable inclined forward as the rear post with the beam piece without a post, these timber, thus put together constitute the side frame of the machine. The width of said machine may be 20 inches between the posts, the sides are joined together

by 14-¹/₂ feet, the lower part consisting of the front posts being
about 13¹/₂ inches (measured on the front side) from where it
enters the bed piece. This post may be two inches deep its
depth extending apiece from the measurement of its width may
lack about $\frac{1}{4}$ of an inch from coming out full with the
front of the post. The mortises in the front posts which receive
the girt may be one and one-half inch from the front side of
the posts and a corner station set at each end of this girt in
front of the tins on sufficient to receive a clean 1¹/₂ inch span
The upper girt over the end of these posts must be set back
from the front to acts as a sort of the same ridge piece. The top
girt in the rear posts may be placed 2 feet of width from the
post where it enters the bed piece. From this girt to the back
end in the front post is placed a board, the upper edge placed
in the lower girt in the front post, to which post it is fastened.
This board as the bottom of the hopper to which are fitted side
boards, extending apiece as far as the top of the side girt
to which to which with the front post they are made fast, the
lower end of the side boards coming within 16 inches of the front
of the post. The bottom board may be proportioned with holes or
construction with slats so as to keep the dirt from the feed
There is a gate or sliding frame stationed between the two
front posts, the side pieces may be 2 feet 6 inches long and
1¹/₂ inches square more the upper and there may be formed
a crop piece 1¹/₂ inch thick and 3 or 4 inches wide. The
tins may pass through the side pieces $\frac{1}{2}$ of an inch which
will cover as tongue which slide in the groove and on the
inside of the front post, at an the lower end of the said
side pieces are other tongues or projecting for the same object
To these side pieces about 9¹/₂ inches below the crop piece
is attached a handle about 3¹/₂ inches wide which is let
in from the front side of these pieces, 3 or 4¹/₂ eighths of an
inch (when it is made fast by solder) which regulates the

thick of the skin is to be cut. The edge of the knife upon the inner side to lay in close contact with the lower end of the bottom board which is not quite full with the front of the gate upon which it rests, so that the knife rests near the front edge of the gate, To prevent it from cutting into the gate something may be attached to the inside of the post, below the gate door piece to receive the blow, A piece of board is to be placed in between the knife and upper door piece to prevent whatever may be in the hopper from falling over the knife when down, If the door piece below the edge of the knife about 1/2 an inch is fastened a board 12 or 15 inches wide against which the contents in the hopper jump when the knife is raised by which means the stones are sliced contact with the edge which stands in from the board & as the gate is pressed down the pieces fall from between the edge of the knife and the board upon a conductor below where the edge of the knife rests, The conductor consists of a board box of iron wire fastened to the underside of door piece made fast to the post, Arrangements for the sliding gate to pass up and down, To prevent the dirt and gravel from working down by the side piece of door gate small plates are made fast to the lower end of the door board which serve as a defences, The gate or sliding frame is raised up and down by means of a long wheel may be 4 feet long perpendicular to the gate at the center of the door piece by means of a pin or bolt two thirds of its distance from the handle end, the opposite end is attached to the left side of the machine by means of a long mortise at the end of the board which receives a tenon which is kept by means of a pin or bolt, all of which forms an elbow,

That part of the elbow upon which the tenon is placed is about 93 inches from the hole where it receives the pin or bolt at the end of the tenon to a hole where it is fastened by another pin or bolt to the left post post, When the face of the knife projects several cutters at right angles with the knife

What I claim as new or as any new invention is the above described machine and for the use of which I wish an exclusive privilege to the principle of propelling, driving and cutting at the same operation together with the application of the jaw and lever accompanied with the lever for propelling and for the use of domestic animals.

In witness whereof I have hereunto subscribed my name the 15th day of February 1831.
